US00D558262S

(12) **United States Design Patent** (10) **Patent No.:** **US D558,262 S**
(45) **Date of Patent:** **** Dec. 25, 2007**

(54) **PORTABLE MOBILE PRINTER**

(75) Inventors: **Yun-Gi Hong**, Seoul (KR); **Seok-Won Bae**, Seoul (KR); **Jun-Won Bae**, Seoul (KR); **Bong-Uk Lim**, Seoul (KR)

(73) Assignee: **Samsung Electronics Co., Ltd.**, Kyunggi-do (KR)

(**) Term: **14 Years**

(21) Appl. No.: **29/261,091**

(22) Filed: **Jun. 7, 2006**

(51) **LOC (8) Cl. 18-02**

(52) **U.S. Cl. D18/50**

(58) **Field of Classification Search** D18/14, D18/19, 36-39, 53-54, 54.1, 55, 4.5; D14/420-425, D14/462-470, 336, 388; 400/613, 613.1-613.4, 400/690.1-690.4, 691-694
